UNITED STATES PATENT OFFICE.

CARL E. JOHNSON, OF RANDOLPH, MASSACHUSETTS.

MACHINE FOR MAKING AND DRIVING TACKS IN WINDOW-SASHES.

No. 888,505.

Specification of Letters Patent.

Patented May 26, 1908.

Application filed July 23, 1906. Serial No. 327,272.

To all whom it may concern:

Be it known that I, CARL E. JOHNSON, a subject of the King of Sweden, residing at Randolph, in the county of Norfolk and 5 State of Massachusetts, have invented new and useful Improvements in Machines for Making and Driving Tacks in Window-Sashes, of which the following is a specification.

10 The object of this invention is to provide a machine for making and driving fasteners for holding glass in position in a sash before the putty is applied thereto. This device is to be used in manufactories where large quantities of glass are set in sashes.

15 The object of the invention is further to provide a device of the character hereinbefore set forth which will be convenient and quick in its operation and which will result in 20 the saving of a large amount of time and also a saving in the cost of the fasteners by which the glass is attached to the sash.

25 The invention consists in the combination and arrangement of parts set forth in the following specification and particularly pointed out in the claims thereof.

30 Referring to the drawings: Figure 1 is a front elevation of my improved machine for making and driving fasteners showing a portion of a sash in section and in position to have a fastener driven therein. Fig. 2 is a side elevation as viewed from the left of Fig. 1. Fig. 3 is a section, partly in elevation, taken on line 3—3 of Fig. 1. Fig. 4 is a section, partly in elevation, taken on line 4—4 of Fig. 2.

35 Like numerals refer to like parts throughout the several views of the drawing.

In the drawings, 8 is a casing or frame suitably formed to be held in the hand of the operator.

40 9 is a raceway extending longitudinally of said casing, through which a wire 10, from which the fasteners are made, is fed. The wire 10 is coiled upon reel 11, rotatably supported upon the pointed ends of screws 12, 12. Said screws are supported in arms 13, 13 upon the upper end of the frame 8 and are locked in position by nuts 14, 14. The wire 45 is fed downwardly by means of two feed rolls 15, 16. Each of said feed rolls has ratchet teeth formed upon its periphery, the feed-roll 16 engaging a spring stop pawl 17 which prevents said roll from rotating in the

55 opposite direction to the arrow thereon (Fig. 3). The roll 15 is rotated in the direction of the arrow thereon (Fig. 3) by a pawl 18 pivoted to a slide 19. A reciprocatory motion is imparted to the slide 19 by a bell-crank lever 20 pivoted upon a stud 21 which is fastened to an arm 22 integral with the frame 8.

60 The bell-crank lever 20 has two arms 23 and 24. The arm 23 is connected by a link 25 to the slide 19 and the arm 24 is connected by a link 26 to a lever 27 pivoted at 28 to the frame 8. The lever 27 is rocked upon its pivot by a lever 29 pivoted to a stud 30 fast to the frame of the machine. The lever 29 has a cutter 31 fast thereto which coacts with a stationary cutter 32 fastened to the frame 8 to sever a portion of the wire 10 therefrom, said portion so severed constituting a fastener 33 (Fig. 4) which is subsequently driven into the sash 34, as herein-after described. The fastener 33 is driven 75 into the sash 34 by a driver 35 which is adapted to be moved transversely of the raceway 9 by a slide 36 to which it is fastened. The slide 36 is constructed to be moved in ways 37, a reciprocatory motion 80 being imparted thereto by a link 38 which connects said slide to the arm 24 of the lever 20.

85 The sash 34, when the fasteners are being driven therein, is located between the right hand side of the frame 8 (Figs. 1 and 4) and a gage 39. Said gage is adjustably fastened to a pin 40 by a set-screw 41, so that said gage can be adjusted toward or away from the frame, thus diminishing or increasing, respectively, the space between the gage and 90 said frame to accommodate different thicknesses of sash.

Having thus specifically described my invention, I will now proceed to describe the general operation of the same: The machine 95 is placed upon the glass 42 of the sash 34, with said sash projecting between the gage 39 and the right hand side of the frame, as shown in Figs. 1 and 4. Assuming the parts to be in the position illustrated in Figs. 1 and 100 4, the operator grasps the frame 8 and presses the upper end of the lever 29 toward said frame. When the lever 29 is thus rocked from the position shown in full lines Fig. 4 to that illustrated in dotted lines 105 therein, the lever 27 is also rocked upon its pivot and through the link 26, the lever 20 is rocked upon its pivot, the arm 24 being

moved toward the right, Figs. 1 and 4, and thus through the link 38 moving the driver 35 toward the right, Figs. 1 and 4, and driving the fastener into the wood of the sash 34. 5 The wire 10 is fed during the movement of the parts just described by the arm 23 of the lever 20 which moves upwardly, thus moving the link 25 upwardly, as well as the slide 19 and pawl 18, until said pawl engages the 10 teeth of the ratchet wheel 15 and rotates said ratchet a portion of a rotation in the direction of the arrow, Fig. 3, thus feeding the wire 10 downwardly. Continued upward movement of the pawl 18 causes the point of 15 said pawl to pass out of engagement with and beyond the ratchet feed wheel 15 in an idle movement and during this time the cutter 31 coöperating with the cutter 32 cuts a fastener 33 from the end of the wire 10, said 20 fastener dropping downwardly in the raceway 9 on the upper face of the driver 35 which at that time is beneath said raceway and is driving the next previously formed fastener. As the driver 35 retracts toward 25 the left, Figs. 1 and 4, until it reaches the position shown in said figures, the fastener which has been resting on the upper face of said driver falls into the position shown in dotted lines, Fig. 4, with its lower end resting upon the upper surface of the glass. 30

It will be noted that the raceway 9 is inclined toward the driver 35 at an obtuse angle thereto and is widened at its lower end, as at 43, so that the fastener falls from the 35 position shown in dotted lines to the position shown in full lines; that is, into a horizontal position lying upon the upper face of the glass in readiness to be driven by the driver 35 which is moved toward the right when 40 the lever 29 is rocked upon its pivot, the upper end of said lever being pressed toward the frame by the operator, as hereinbefore described.

The lever 29 is moved from the position 45 shown in dotted lines to the position shown in full lines (Fig. 4) either by the operator moving the same positively by hand, or it may be moved by means of a spring (not shown in the drawings) interposed between 50 the lever 29 and the frame 8. When said lever is moved from the position illustrated in dotted lines (Fig. 4) to that shown in full lines, the different parts hereinbefore referred to will be moved back into the positions illustrated in full lines in the drawings 55 and the mechanism will be in condition to be moved along the sash in readiness for the making and driving of another fastener.

Having thus described my invention, what 60 I claim and desire by Letters Patent to secure is:

1. In a machine for driving fasteners, a casing, a raceway, a driver for said fasteners, a pivoted arm connected to said driver, a

lever, a link connecting said arm to one end 65 of said lever, and a hand lever pivoted to said casing and connected to said first lever, whereby said driver may be moved transversely of said raceway.

2. In a machine for driving fasteners, a 70 casing, a raceway, mechanism to feed a wire longitudinally of said raceway, a driver for said fasteners, a pivoted arm connected to said driver, a lever, a link connecting said arm to one end of said lever, a hand lever 75 pivoted to said casing and connected to said first lever, whereby said driver may be moved transversely of said raceway, a cutter fast to said hand lever and adapted to be moved thereby across said raceway, and a 80 stationary cutter fast to said casing and adapted to coöperate with said first cutter to sever from said wire a portion thereof to form a fastener.

3. In a machine for driving fasteners into 85 a window sash, a stationary raceway for said fasteners, a driver adapted to be moved transversely of said raceway, mechanism to feed wire longitudinally of said raceway, and mechanism to sever a portion of said wire 90 therefrom to form a fastener, the lower portion of said raceway inclined toward said driver at an obtuse angle thereto, whereby said fastener is adapted to fall into a horizontal position in front of said driver. 95

4. In a machine for driving fasteners into a window sash, a casing, a raceway, a driver for said fasteners, a bell-crank lever, one arm of which is connected to said driver, a slide, a link connecting said slide to the other arm of said bell-crank lever, a pair of feed wheels, means carried by said slide to actuate said feed wheels to move a wire longitudinally of said raceway, a second lever, a link connecting said first arm of said bell-crank lever to 100 said second lever, and a hand lever pivoted to said casing and connected to said second lever, whereby said driver may be moved transversely of said raceway. 105

5. In a machine for driving fasteners, a 110 casing, a raceway, a driver for said fasteners, a bell-crank lever, one arm of which is connected to said driver, a slide, a link connecting said slide to the other arm of said bell-crank lever, a pair of feed wheels, one of 115 which constitutes a ratchet, a pawl carried by said slide and adapted to operatively engage said ratchet, a second lever, a link connecting said first arm of said bell-crank lever to said second lever, and a hand lever pivoted to said casing and connected to said second lever, whereby said driver may be moved transversely of said raceway. 120

6. In a machine for driving fasteners, a 125 casing, a raceway, a driver for said fasteners, a bell-crank lever, one arm of which is connected to said driver, mechanism to feed a wire longitudinally of said raceway, said

mechanism connected to the other arm of
said bell-crank lever, a second lever, a link
connecting said first arm of said bell-crank
lever to said second lever, and a hand lever
5 pivoted to said casing and connected to said
second lever, whereby said driver may be
moved transversely of said raceway.

In testimony whereof I have hereunto set
my hand in presence of two subscribing wit-
nesses.

CARL E. JOHNSON.
